UNITED STATES PATENT OFFICE.

LEANDER S. WOODBURY, OF CALUMET, MICHIGAN.

ROCK-DRILL.

SPECIFICATION forming part of Letters Patent No. 321,670, dated July 7, 1885.

Application filed February 2, 1885. (No model.)

To all whom it may concern:

Be it known that I, LEANDER S. WOODBURY, a citizen of the United States, residing at Calumet, in the county of Houghton and State of Michigan, have invented new and useful 5 Improvements in Rock-Drills, set forth in the annexed specification.

My invention relates to the mechanism in a rock-drill whose office it is to rotate the drill 10 as it is entering the rock, its object being, first, to avoid the unequal lateral strain that comes upon the rotating bar as heretofore used and the derangement incident thereto; second, to decrease the number of parts most 15 affected by wear; third, to prevent the air, which, being retained in the cylinder, acts as a cushion to prevent the piston from striking the cylinder-head, from escaping into the casting containing a part of the rotating mechanism. These objects are accomplished in the device illustrated in the accompanying drawings, in which—

Figure 1 is a longitudinal central section of the upper end of a rock-drill cylinder, cylinder-head, piston-head, &c., as on line x x , Fig. 12, the rotating-bar being shown in elevation. Fig. 2 is a plan of the ring K, Fig. 1, looking from above, with a cross-section of the rotating bar C where it passes through the ring. Fig. 3 is a plan of the rotating disk H, Fig. 1, looking from below, with a cross-section of the rotating bar C where it passes through the disk. Fig. 4 is an end elevation of the rotating bar C, Fig. 1, looking from X. Fig. 5 is an end elevation of the rotating bar C, Fig. 1, looking from Y. Fig. 6 is a side elevation of a portion of ring K and rotating disk H, for the purpose of showing how the latter engages with the former. Figs. 7 and 8 are modifications of the section of the rotating bar C where it passes through the disk H. Fig. 9 is a plan of the washer W, Fig. 1. Figs. 10 and 11 illustrate a modification of the ring K, the former being a section on line x x of Fig. 11, which is a plan corresponding to that of Fig. 2. Fig. 12 is a plan of the cylinder-head incasing the ratchet and pawls of the rotating device heretofore used, looking from the bottom, with a cross-section of the rotating bar 50 where it passes through the head. This figure is for descriptive purposes, to more clearly illus-

trate the first object of my invention, as heretofore specified.

Similar letters refer to similar parts throughout the views illustrating my invention, and 55 as far as possible in Fig. 12.

A is a portion of the upper end of a rock-drill cylinder. B is the upper end of the piston, P being the packing in the same.

O is a composition-nut firmly screwed into 60 the end of the piston, made internally to conform to the shape and pitch of the spiral wings of the rotating bar C.

L is a metallic disk for the purpose of holding the packing-ring R, which is of some 65 fibrous material—as leather or compressed or vulcanized fiber.

D is the cylinder-head, into which is firmly 70 screwed the disk K against the shoulder I, Fig. 1, and upon the upper face of which are cut the ratchet-teeth, as shown more clearly in Figs. 2 and 6.

The modification of the ring K shown in 75 Figs. 10 and 11 simply dispenses with the thread cut upon its periphery, as shown in Fig. 1; and to perform the same function the ears z z are extended, as on the dotted lines z z , Fig. 1, and through which the bolts M pass, preventing the ring from turning.

C is an elevation of the rotating bar, which 80 is in one piece, that portion below the collar T being of the usual form.

T is a solid collar upon the rotating bar, a cross-section of which, as shown, is hexagonal. It may, however, have any polygonal shape, 85 or such modifications in shape as indicated by Figs. 7 and 8.

V is also a solid collar on the end of the rotating bar to give a bearing in the head D. It also serves as an abutment for the spring S, 90 which may either be wound in its place or twisted into place through the hole V', Fig. 5.

H is a disk fitted upon the collar T of the rotating bar, so that it will rotate with the bar, at the same time being perfectly free to 95 slide upon it. This disk also has teeth cut upon one face to correspond with and mesh into those upon the disk K, as shown in Figs. 3 and 6. Into the back of this disk is fitted the collar or washer W, which is cut in halves, 100 and having been driven into the disk the edges of the disk around it are staked down upon it,

so that it is practically solid with the disk, and its office is to receive the thrust of the spring S. Through the disk H is drilled a small hole, U, which is simply an air-connection between the spaces above and below the disk.

5 M are bolts, which, extending through the lower head, bolt the whole drill together.

F is a cross-bar, between which and the head D is a rubber buffer, N, which receives the 10 shock when from any cause the piston-head strikes the cylinder-head.

In Fig. 12, D is the cylinder-head. C is a section of the rotating bar where it passes through the head, and corresponds to the same 15 section in Fig. 2. H is the collar, having ratchet-teeth upon its periphery, into which engage the pawls J, which pivot upon the pins g, being kept engaged by springs. (Not shown.)

20 Having thus described the parts, I will proceed to describe their operation and use. In all rock-drills in which the motion of the drill is reciprocating, it is necessary that it should also have a rotary motion for the purpose of 25 making a round hole and keeping itself clear in the hole. This rotary motion is given by the spiral bar C, which is common to most rock-drills. The downward motion of the piston gives a rotary backward motion to the 30 bar C in both devices, as indicated by the arrows, Figs. 3, 6, and 12, the shape of the teeth lifting the pawls in Fig. 10 and sliding back the disk H upon the collar T in Fig. 1. The 35 re-engagement of the pawls in the ratchet-wheel, Fig. 10, and of the teeth of the disk H, with those of the disk K, Fig. 1, prevents any motion the other way, so that when the piston is coming up it is given the rotary motion, and, as regards the rotary motion of the drill, the 40 same results obtain in both cases so long as the devices properly perform their function.

Referring now to Fig. 12, I proceed to show the derangements alluded to, and to avoid which is the main object of my invention. 45 It will be plainly seen that the resistance to the rotary motion of the rotating bar when the piston is coming up is all on one side of the ratchet-wheel H. As the piston moves over the bar with great rapidity and the inclination of the spiral is comparatively small, the force brought against the pawls is very great, and was the occasion of the use of two pawls in order that the strain might be divided. Now, as regards the bar C, the resultant of this force is in the direction indicated by the dotted arrow, and comes against the head D with even greater force than upon the pawls, and the hole through the head becomes worn in that direction, as indicated by the 50 dotted line Z, and the bar itself, becoming also worn at this place, very soon has considerable lateral motion, resulting in two serious evils: first, if no especial means are used to prevent the escape of pressure around the bar 55 into the head, when the bar becomes loose, as above described, then the air that is retained in the cylinder, as in space E, Fig. 1, for the

purpose of a cushion, has a chance to expand into the spaces around the ratchet-wheel and pawls, and often does so to such an extent as 70 to render the cushion insufficient to prevent the piston from striking the cylinder-head, and damage to the drill is often the result; second, in order that the pawls J shall each receive its share of the strain, it is not only 75 necessary that the teeth be accurately spaced and the pawls so adjusted that both will take the strain at the same time, but having been so adjusted it is also necessary that the relative position of the center of the bar C with 80 the center of the pins g be sustained, but the wear of the head and bar, as above described, destroys this relation, and as a consequence the strain comes greater upon one pawl than upon the other, and oftentimes it comes entirely upon one pawl, which, being unable to bear it, the points of the pawls become broken or battered to such an extent that repairs become necessary, and the same is also true of the teeth of the ratchet. One other difficulty follows. In order that the nut O, Fig. 1, may work with the greatest freedom, the bar C should be perfectly central through its length; but when any lateral motion is possible, such as has been described, the bar is 95 thrown out of a true central line, especially as the piston is coming up and when the greatest strain is upon it, so that it is more or less cramped in the nut, and undue friction is the result.

Having thus far described the derangements peculiar to the old device, partially illustrated in Fig. 12, and which are not mere theoretical deductions, but the actual results of experience, I will proceed to more fully 105 explain my invention, by which these derangements are fully and practically overcome, referring to the figures illustrating my invention. The action of the piston upon the bar, being the same as with the old device, 110 when the piston is going down, the bar C, with the disk H, has a backward motion, the disk H sliding upon the collar T as it revolves from one tooth to another of the disk K, the spring S keeping the disk H engaged with the 115 disk K, and always locking it when it has a tendency to move forward. The teeth of both disks are accurately cut, so that whatever be the portion of the rotation in which they are locked every tooth of the disk H bears equally 120 against its mate in the disk K, so that when the piston is coming up the resistance to its tendency to rotate the bar C forward is equal all around the disk H, and no lateral strain whatever comes upon the bar C. The wear 125 upon the ring K, through which the bar passes, and upon the bar itself at this point is reduced to the minimum, as is also the friction of the bar within the nut O, while the strain upon the teeth of the disks H and K is so 130 widely distributed and brought to bear upon such an increase of surface presented by so many teeth the wear at this point also is reduced to the minimum. Aside from the ro-

tating bar, the parts within the head of the old device subject to wear are the two pawls, two springs, and the two pins *g*—six parts in all. In my invention the disk H and washer W, being practically one piece, the parts aside from the bar subject to wear are the disk K, (teeth only,) the disk H, and the spring S—three parts in all. This covers the second object of my invention. To absolutely prevent any escape of pressure from the space E into the head D, I make use of the packing-ring R, held firmly in place by the ring L. This ring R is formed in one piece, of some fibrous material—as leather, or compressed or vulcanized fiber—which is of a yielding nature. It will be seen that any pressure within the space E will keep the packing-ring R close to the bar C, effectually shutting off all escape in that direction, so that if the piston-
packing P is also tight the desired cushion within the space E is obtained.

The ring R is cheaply made, and readily replaced when worn out by the one using the drill.

25 The spirally-formed portion of the rotating bar C is common.

No claim is made upon the clutch H K, simply as such.

The combination of the various parts described, their operation, and purpose are new.
30 I therefore claim—

1. The combination, in a rock-drill, of the

rotating bar C, the clutch H K, the washer W, spring S, and cylinder-head D, when one part of the clutch is fixed and forms a guide 35 for the bar and the other part is so attached to the bar as to rotate with it, and at the same time slide upon it, when the purpose of the combination is to rotate the piston of a rock-drill, and the parts operating to that end, except the spiral portion of the bar, are within the cylinder-head.

2. The combination, with the rotating bar, of a rock-drill, made substantially as and for the purpose herein described, with the fixed part K 45 of the rotating clutch, the ring L, the fibrous packing R, and the cylinder-head D, when the fixed part of the clutch is attached to the cylinder-head, substantially as shown, the packing-ring R being formed with a cylindrical body flanged at one end for the purpose of being held between the disk K and ring L, the latter being recessed to allow a free admission around the body of the packing-ring of any pressure within the cylinder, the tendency of which is to close the packing-ring around the rotating bar for the purpose of preventing any escape of pressure around the bar.
